UNITED STATES PATENT OFFICE.

DEWITT A. BRUNETT, OF MINNEAPOLIS, MINNESOTA.

AUXILIARY HOT-WATER AND HEATING SYSTEM.

1,402,045.

Specification of Letters Patent.

Patented Jan. 3, 1922.

Application filed February 16, 1920. Serial No. 358,814.

To all whom it may concern:

Be it known that I, DEWITT A. BRUNETT, a citizen of the United States, residing at Minneapolis, in the county of Hennepin 5 and State of Minnesota, have invented certain new and useful Improvements in Auxiliary Hot-Water and Heating Systems, and I do hereby declare the following to be a full, clear, and exact description of the invention, such as will enable others skilled

in the art to which it appertains to make and use the same.

My invention has for its object to provide an improved auxiliary heater for use in hot 15 water and steam heating systems, and by the use of which, the hot gases that are usually passed to the chimney or stack, and hence wasted, are utilized in the heating of hot water or generation of steam in the 20 heating system.

Generally stated, the invention consists of the novel devices and combination of devices hereinafter described and defined in the claims.

25 The invention is illustrated in the accompanying drawings wherein like characters indicate like parts throughout the several views.

Referring to the drawings:

30 Fig. 1 is a view partly in elevation and partly in vertical section on the line 1—1 of Fig. 2, illustrating my invention as applied in a hot water heating system; and

Fig. 2 is a horizontal section on the irregular line 2—2 of Fig. 1.

The numeral 3 indicates a hot water heater and the numeral 4 one of the several radiators, such as used in hot water heating systems. The numeral 5 indicates a hot 40 water delivery pipe that extends from top of the heater 3 to the radiator 4. The numeral 6 indicates the customary smoke pipe that extends from the combustion chamber of the heater 3. The numeral 7 indicates a 45 chimney or smoke stack.

The auxiliary heater comprises an outer shell 8, and an inner shell 9, which shells are connected to afford an intervening water chamber 10. Within the inner shell 9, there 50 is formed a hot gas chamber 11, and this chamber, as shown, extends into the lower portion of the outer shell 8. The smoke pipe 6, from the heater 3, extends through the shells 8 and 9 at one side and opens 55 into one side of the hot gas chamber 11. An upper secondary smoke pipe 12 leads out-

ward from the upper portion of the said chamber 11, through both shells 8 and 9, and opens into the smoke stack 7; and a similar but lower secondary smoke pipe 13 60 leads outward from the lower portion of said chamber 11, and also opens into the smoke pipe 7. Dampers 12^a and 13^a, respectively, in the smoke pipes 12 and 13, adapt the same to be independently opened 65 and closed.

Located within the hot gas chamber 11 is an auxiliary heater, preferably made up of a plurality of connected hollow sections 14 which may be of radiator construction, and 70 these sections are connected at their upper and lower ends, and at their lower ends are also connected at 15 to the lower portion of the hot water chamber 10. A cold water return pipe 16 extends from the radiator 4 75 to the upper portion of the hot water chamber 10, and a secondary return pipe 17 extends from the upper portion of the auxiliary heater 14, back to the lower portion of the hot water chamber of the main 80 heater 3.

The operation of the auxiliary heater in a hot water heating system in the arrangement described is, as follows:

The main heating of the water will take 85 place in the main heater 3 and the hot water will rise through the pipe 5 to the radiator or radiators 4, while the relatively cold water from the radiator or radiators will be returned through pipe 16, thence through 90 water chamber 10, thence through auxiliary heater 14, and thence through pipe 17 back to the main heater 3.

The hot gases from the heater 3 will pass into hot air chamber 11 of the auxiliary 95 heater and will come into contact with all of the exterior surface of the auxiliary heater 14, and from thence, will pass to the smoke stack, either through secondary smoke pipe 12 or secondary smoke pipe 13. In 100 starting a fire, damper 12^a will be open, and damper 13^a closed, but after the fire has been started, damper 13^a will be open and damper 12^a will be closed, so that under ordinary conditions, the only escape of the 105 hot gases from hot air chamber 11 to the smoke stack or chimney 7 will be through the lower secondary smoke pipe 13.

Hence, as is evident, the cold water returning from the radiator or radiators 4, 110 in passing through the auxiliary heater, will be heated to a considerable extent, so that

it will be returned to the main heater 3 in quite warm condition, and hence, the heat produced in the main heater will be effective to raise the temperature of the water to a much higher degree than is the case where the cold water is returned directly from the radiators to the main heater. Thus, also, it is evident that the hot water heating system is not only rendered more efficient for a given fuel consumption, but is made quicker in its action, as well as more economical in the use of fuel.

When the auxiliary heater is applied in a steam heating system the action will be very similar to that above described, but it will then be condensed steam or cooled water vapor that will be passed through the auxiliary heater.

Obviously, the auxiliary heater may be very easily and cheaply installed in connection with hot water and steam heating systems already in use, as well as in installations.

What I claim is:

1. A water heater having in combination a casing, a second casing surrounding said casing and spaced therefrom to form a water chamber, a water inlet means at the top of said chamber, a hollow heated member disposed in said first mentioned casing communicating with said water chamber at the bottom thereof, a water outlet means at the top of said heated member, and means for passing a heating medium through said first mentioned casing.

2. A water heater having in combination a casing, a second casing surrounding said casing at the sides and top and spaced therefrom to form therewith a water chamber, a water inlet means at the top of said chamber, a hollow heated member disposed in

said first mentioned casing communicating with said water chamber at the bottom thereof, a water outlet means at the top of said heated member, a conduit for a heating medium communicating with one side of said first mentioned casing, and upper and lower damper-equipped outlet conduits at the other side of said casing.

3. The structure set forth in claim 1, said hollow heated member comprising a plurality of connected hollow sections.

4. A water heater having in combination a casing, a second casing surrounding said casing at the side and top and forming therewith a water chamber, a water inlet means at the top of said chamber, a water outlet means connecting to the bottom of said water chamber and passing out of said inner casing at the top thereof, a conduit for a heating medium connected to the inside of said first mentioned casing at one side thereof, and upper and lower outlet conduits extending from said casing at the other side thereof.

5. A fluid heater having in combination a casing, a second casing outside of said casing and spaced therefrom to form therewith a fluid chamber, a hollow heating member disposed in said first mentioned casing, and spaced from the walls thereof, means for circulating a fluid through said heating member, and means for passing a heated medium through said second mentioned casing about said heating member.

In testimony whereof I affix my signature in presence of two witnesses.

DEWITT A. BRUNETT.
